UNITED STATES PATENT OFFICE

HARRY E. MOYSES, OF AKRON, OHIO

DEVICE FOR PICKING UP GOLF BALLS AND LIKE ARTICLES

Application filed January 10, 1930. Serial No. 419,814.

This invention, as indicated, relates to devices for picking up golf balls, or other like spherical or approximately spherical articles, the surface of which may be corrugated or otherwise formed so that an ordinary vacuum cup would be inapplicable. More specifically the invention has for its object the provision of a novel vacuum cup attachment for a golf club which will enable a player to lift a ball 10 from a green cup without bending or stooping. A more particular object is to provide a means firmly gripping a ball when it is inaccessible or inconvenient to reach with the hand under all conditions.

15 To the accomplishment of the foregoing and related ends, said invention, then, consists of the means hereinafter fully described and particularly pointed out in the claims, the annexed drawings and the following description setting forth in detail certain mechanism embodying the invention, such disclosed means constituting, however, but one of various mechanical forms in which the principle of the invention may be used.

20 25 In said annexed drawings:—

Fig. 1 is a side elevation of a golf club having my improved device attached thereto; Fig. 2 is a view of the attachment in operation; Fig. 3 is a detail section of the device, showing the relation in size between it and a ball; and Fig. 4 is an enlarged section of the device actually gripping a ball.

Heretofore springs and other devices have been used to pick up golf balls, but it has been 30 found that they will not work every time and in some cases these devices have injured the cover of the ball. In my improved device the ball is gripped firmly by means of suction which results in efficient operation and 35 no injury to the ball. Golf is a game that is played under all conditions; that is, early in the morning when sweaters and coats are worn, and in the event that a ball is driven into a water hazard, it is necessary to remove 40 such garments and reach into the water and pick up the ball. All of this detracts from the enjoyment of the game and is liable to result in colds to the player. Under some circumstances, the water may be too deep to 45 reach by hand and it is necessary to push the ball around with the club and eventually knock it on shore. By the use of my improved pick-up device, all such inconvenience and danger is obviated. It is merely necessary to reverse the club, grip it by the club head, 55 and press downwardly on the ball.

In Fig. 1, I have shown a conventional golf club having a shaft 1, a club head 2, and a wrapped handle 3, with my improved vacuum cup 4 attached to the handle. In Fig. 2, 60 a green 8 is illustrated, having a cup 9 therein, with a ball in the cup and the club 1 in position to pick up the ball from the cup without having to bend over or stoop. In the same manner a ball could be picked up 65 from a water hazard, such as a lake or brook, without the player removing his sweater or coat and without the necessity of wetting his hand or arm. In Fig. 3 the device is shown in detail and here is illustrated the 70 difference between the normal diameter of the beveled annular portion 7 and the outer surface of the ball. Immediately below the beveled surface 7, I provide a recess 6, preferably approximately spherical in form, that 75 constitutes the vacuum cup proper, and on the other end of the retriever I have shown a cavity 10 which, due to the resiliency of the material of the device, will fit any ordinary golf club. In Fig. 4, the device is shown 80 with the outermost portion, including the beveled surface 7, expanded to grip a ball and with the recess 6 at the same time functioning as a vacuum cup. In this manner 85 the ball is securely gripped by the suction exerted by such cup, since the beveled annular portion that surrounds the cavity 6 is of sufficient width to seal the irregular surface of a spherical article, such as a golf ball. That is, the bevelled portion has a 90 width which is sufficient to seal a part of the surface of a golf ball, and as shown in Fig. 4 this part need not be the largest portion of the surface, but may be a smaller portion, 95 thus dispensing with the necessity for a large cumbersome device which might interfere with a player's movements. In other words, the bevelled annular portion grips a segment of the surface of a spherical object 100 which may be a golf ball instead of gripping

an equatorial portion. It will be understood that by simply pushing the device down on the ball, most of the air is exhausted from such cavity 6 and the ball thereby held by suction. This device has been tried under all conditions and it has been found that it satisfactorily picks up the ball by simply pushing the club downwardly.

While the foregoing specification has described my device more especially as a golf ball device, it is not intended to limit the invention to one use as there are innumerable other objects with which it can be efficiently used. For instance, my vacuum cup could be used to replace worn out electric bulbs in inaccessible places. Such a use would be more easily accomplished than with a golf ball for the surface of a bulb is smooth, whereby it is easily gripped with my cup. In replacing worn out bulbs at present, especially on theatre marquees and signs, the electrician or other workman must use a ladder, whereas with my cup placed on a long stick a bulb could be quickly removed and a new one installed, thus dispensing with the use of ladders or equivalent means, and saving the time which such means require.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. As an article of manufacture, a vacuum cup for picking up spherical articles such as golf balls and the like, comprising a flexible member having an approximately frusto-conical exterior surface, and a cavity in one end thereof, said cavity consisting of an annular beveled surface intersecting said exterior surface and forming a thin lip and another central cavity located interiorly of said beveled surface.

2. As an article of manufacture, a vacuum cup for picking up spherical articles such as golf balls and the like, comprising a flexible member having an approximately frusto-conical exterior surface, and a cavity in one end thereof, the wall of said cavity consisting of an annular beveled surface intersecting said exterior surface and another central cavity located interiorly of said beveled surface, said exterior surface and beveled surface forming a thin expansible lip.

3. As an article of manufacture, a vacuum cup for picking up spherical articles such as golf balls and the like, comprising a flexible member having an approximately frusto-conical exterior surface, and a cavity in one end thereof, the wall of said cavity consisting of an annular beveled surface intersecting said exterior surface and forming a thin lip

and another central cavity located interiorly of said beveled surface, that portion of said exterior surface adjacent said beveled surface flaring outwardly.

4. As an article of manufacture, a vacuum cup of flexible material having means on one of its ends for attachment to a golf club, the other end of said cup having a central cavity therein, the outermost portion of which has an annular beveled surface of substantial width, said surface and the exterior surface of said cup forming a thin flaring lip.

Signed by me, this 8th day of January, 1930.
